[57] CLAIM

The ornamental design for a room deodorant dispenser, as shown.

DESCRIPTION

FIG. 1 is a front isometric view of a room deodorant dispenser showing our new design;

FIG. 2 is another front isometric view thereof, showing the louvers in an open position;

FIG. 3 is a front elevational view thereof;

FIG. 4 is a top plan view thereof;

FIG. 5 is an end elevational view thereof;

FIG. 6 is a rear elevational view thereof; and

FIG. 7 is a cross sectional view taken on line 7—7 of FIG. 3.
